UNITED STATES PATENT OFFICE.

MICHAEL RAUGHTIGAN, OF NORWICH, CONNECTICUT, ASSIGNOR OF ONE-HALF TO FRANK C. TURNER, OF SAME PLACE.

DASH-POT.

SPECIFICATION forming part of Letters Patent No. 434,951, dated August 26, 1890.

Application filed July 2, 1890. Serial No. 357,569. (No model.)

To all whom it may concern:

Be it known that I, MICHAEL RAUGHTIGAN, a citizen of the United States, residing at Norwich, in the county of New London and State 5 of Connecticut, have invented a certain new and useful Improvement in Dash-Pots, which improvement is fully set forth and described in the following specification, reference being had to the accompanying sheet of drawings, in which—

Figure 1 is a side elevation of a dash-pot of my improved construction, and Fig. 2 a longitudinal sectional view of the same.

This invention is in so-called "dash-pots" 15 used for cushioning various forms of mechanisms by means of a liquid confined within a suitable receptacle and controlled by a piston or plunger being connected to and adapted to move with an operative part of the machine 20 with which said complete dash-pot is connected. Dash-pots of this class have been used commonly and are valuable aids in current-regulating mechanisms for dynamo-electric machines, a familiar example of such 25 adaptation being seen in United States Patent No. 238,315, issued March 1, 1881, the dash-pot being therein utilized to prevent any too sudden movement of the armature.

The immediate object of my present invention 30 is to provide a means of communication between the adjacent chambers of the dash-pot to the end that the flow of liquid through or past the piston may be more perfectly controlled than heretofore; also, to provide a 35 form of regulating mechanism that may be adjusted, if desired, without stopping the dynamo or other machine to which the dash-pot is connected.

Referring to the annexed drawings, the letter *a* indicates the cylindrical shell of my dash-pot, having a screw-cap *b* at one end and a perforated lug *c* at the opposite end, by means of which said cylinder may be connected to the machine.

40 *d* indicates a piston or plunger fitted to slide in the cylinder *a*, said piston being attached to a rod *e*, that projects outward through the

screw-cap *b* and terminates in a lug-fastening *e'*, substantially like the described lug-fastening *c*. 50

In the lower end of the piston-rod *c* is bored a vertical hole *f*, which leads upward and connects with lateral openings *g*, as shown in Fig. 2, thus providing a free and unobstructed passage between the compartments of cylinder *a* above and below the piston. 55

The piston-rod *e* is screw-threaded throughout a portion of its length, and on said rod is an internally-threaded tubular section *i*, having at its upper end a flanged head or thumb 60 piece *k*, that may be used as an operating-handle to rotate the tubular section *i* on the piston-rod *e*. The lower end of said tubular section is preferably formed as an enlarged head *j*, which abuts the piston *d* when the 65 tube *i* is screwed downward on the piston-rod *e* and forms a tight valve to prevent the passage of liquid through the openings *f* and *g*. By varying the height of tube *i* on the piston-rod *e*, more or less of holes *g* may be 70 exposed and the flow of liquid through said holes controlled. The head *j* on tube *i* may be omitted; but I prefer the form shown in the drawings, as it insures a more perfect fit with the piston *d*. The resistance of the liquid when the dash-pot is in use is of course 75 proportionate to the ease with which said liquid may escape under pressure, and it will be readily understood that the valve mechanism above described allows the operator in charge 80 to vary the degree of resistance as circumstances or judgment may direct.

Having described my invention, I claim—

The combination, in a dash-pot, of an enclosing shell, piston, and piston-rod having a 85 central longitudinal opening with lateral openings, as set forth, and a tube fitted to move longitudinally on said piston-rod to cover or expose said lateral openings, for the purpose specified.

MICHAEL RAUGHTIGAN.
